PEDAL ACTUATED ROUND-ABOUT

Alvah W. Fowler, Fort Worth, Tex.

Application November 12, 1953, Serial No. 27,549

Term of patent 14 years

(Cl. D34—5)

Fig. 1.

Fig. 2.

To all whom it may concern:

Be it known that I, Alvah W. Fowler, a citizen of the United States of America, residing at Fort Worth, in the county of Tarrant and State of Texas, have invented a new, original, and ornamental Design for a Pedal Actuated Round-About, of which the following is a specification, reference being had to the accompanying drawing, forming part thereof.

Figure 1 is a perspective view of a pedal actuated round-about embodying my new design, and

Figure 2 is a plan view thereof.

I claim:

The ornamental design for a pedal actuated round-about, substantially as shown.
